UNITED STATES PATENT OFFICE.

ADEN L. FILLMORE, OF PITTSBURGH, PENNSYLVANIA.

PITCH-PIPE.

1,125,502.

Specification of Letters Patent.

Patented Jan. 19, 1915.

Application filed December 31, 1912. Serial No. 739,517.

To all whom it may concern:

Be it known that I, ADEN L. FILLMORE, a citizen of the United States, residing at Pittsburgh, in the county of Allegheny and State of Pennsylvania, have invented a new and useful Improvement in Pitch-Pipes, of which the following is a full, clear, and exact description, reference being had to the accompanying drawings, forming part of this specification, in which—

Figure 1 is a plan view of a preferred form of pitch pipe embodying my invention; Fig. 2 is an edge view of the same; Fig. 3 is a section on the line III—III of Fig. 2; Figs. 4 and 5 are perspective views of two of the members of the device.

My invention has relation to pitch pipes, and is designed to provide a pitch pipe of simple construction and convenient form.

Referring to the accompanying drawings, the numeral 2 designates the bottom member of the pitch pipe, which is formed with a plurality of transverse grooves or recesses 3, closed at one end and open at the opposite end, and which are designed to form separate air chambers for the different reeds of the device. 4 designates the reed plate having a series of openings 5, of different lengths and each provided with a reed 6.

This plate fits the upper surface of the bottom member 2 and has a right-angled flange 5^a, which fits the edge of the member 2 through which the recesses 3 extend, said flange having a plurality of openings 7, registering with the open ends of said recesses.

8 designates a convex cap plate, which is secured to the reed plate and which is

marked with letters or other characters representing various notes.

10 designates a mouth piece which is mounted to slide along the device so as to be brought into position to register with any one of the openings 7. This mouth piece is formed with guide flanges 11, which slidably engage the projecting edge 5^b of the flange 5^a and a projecting rib 12 on the cap plate 8. The mouth piece is also formed with a pointer extension 13, which, as the mouth piece is moved, is brought opposite any one of the indications of the cap plate.

By moving this mouth piece to a position at which the pointer indicates the desired note, a corresponding note may be produced by blowing in the mouth piece.

I claim:

A pitch pipe, comprising a bottom plate having a plurality of recesses open at one side and end, an angled reed plate secured over said recesses, said reed plate having reed-containing slots over the open sides of said recesses, a cap-plate secured over the slots in the reed plate, and having markings thereon, and a mouth piece mounted to slide longitudinally over the open sides of said recesses, said mouth piece having a pointer extension which co-operates with the markings on the cap-plate, substantially as described.

In testimony whereof, I have hereunto set my hand.

ADEN L. FILLMORE.
